UNITED STATES PATENT OFFICE

EDWARD MALLINCKRODT, JR., OF ST. LOUIS, AND HENRY V. FARR, OF FERGUSON, MISSOURI, ASSIGNORS TO MALLINCKRODT CHEMICAL WORKS, OF ST. LOUIS, MISSOURI, A CORPORATION OF MISSOURI

METHOD OF AND APPARATUS FOR PACKAGING

Application filed March 14, 1927, Serial No. 175,096. Renewed February 29, 1932.

This invention relates broadly to a method of, and apparatus for packaging materials; and with regard to certain more specific features, to a method of, and apparatus for 5 packaging ether or a like perishable material.

Among the several objects of the invention may be noted the provision of relatively high-speed, automatic means for packaging ether 10 which is used for anaesthesia and other purposes, where all possible deterioration during periods of storage should be prevented; the provision of improved automatic means for packaging ether or the like out of the presence of air or a similar fluid deleterious to 15 the ether or the like, and packaging it in the presence of an inert fluid such as gaseous nitrogen or a like non-deleterious fluid; the provision of improved automatic means for 20 replacing the air found in the packages to be used, by the said inert gas, prior to the packaging process per se and using said inert gas ambiently during the packaging process; the provision of a means of the class described 25 which requires for its separate elements of construction only inherently rugged members, which can be depended upon to provide continuous and satisfactory service; and the provision of apparatus for carrying 30 out the process described which shall be low in cost and upkeep, and which is simple in operation and in manipulation.

Another object of the invention is to displace the deleterious fluid such as air in the 35 packages with a non-deleterious fluid such as nitrogen and also to absorb the deleterious fluid by diffusion.

Another object of the invention is to provide a counter current between the deleterious 40 and the non-deleterious fluids in order to effect a saving in quantities of non-deleterious fluid used.

Another object of the invention is to provide improved means for weighting the non-deleterious fluid so that it will properly displace the deleterious fluid, the weighting material comprising the fluid being packaged or other suitable heavier material such as argon or the like.

50 Another object of the invention is to pro-

vide simple means for compensating a plurality of measured liquid charges for temperature changes.

Other objects will be in part obvious and in part pointed out hereinafter.

In the patent application of Edward Mallinckrodt, Jr., Serial No. 118,440, filed June 25, 1926, was disclosed a method for packaging materials in which alternate evacuations were made from chambers carrying the packages to be filled and the device as a whole was maintained in an ambient atmosphere of non-deleterious fluid.

The present invention involves either or both the method of diffusion or displacement between the non-deleterious and deleterious fluid. No evacuations are used, nor is the device as a whole maintained in an ambient atmosphere of non-deleterious fluid, although the fluid being filled is maintained in an ambient atmosphere of non-deleterious fluid. These two methods, it is believed, present the only means for accomplishing the end sought, namely, the automatic packaging of pure ether.

The invention accordingly comprises the elements and combination of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a side elevation of the machine showing the approximate slope thereof;

Fig. 2 is a plan view of the device showing certain parts broken away;

Fig. 3 is a fragmentary plan view of a dial feed mechanism;

Fig. 4 is a vertical section taken substantially on line 4-4 of Fig. 18 and shows a valve and cam plate;

Fig. 5 is a fragmentary vertical section taken on line 5-5 of Fig. 19;

Fig. 6 is a vertical section taken through one of the can filling units of the device, showing a can in its lowered position;

Fig. 7 is a view similar to Fig. 6 showing

the can lifted and being supplied with ether and nitrogen;

Fig. 8 is a view similar to Fig. 6 but showing a can being pushed from the device at another position during its circular movement;

Fig. 9 is a fragmentary side elevation of the supply chamber, certain portions being broken away;

Fig. 10 is a fragmentary section taken on line 10—10 of Fig. 12;

Fig. 11 is a view similar to Fig. 10 taken on line 11—11 of Fig. 12;

Fig. 12 is a cross section taken substantially on line 12—12 of Fig. 10;

Fig. 13 is an enlarged section taken on line 13—13 of Fig. 2, showing parts broken away;

Fig. 14 is a cross section taken on line 14—14 of Fig. 13 but showing certain added parts not shown in said Fig. 13;

Fig. 15 is a view similar to Fig. 14 taken clockwise and to the right thereof, when the machine is viewed from above;

Fig. 16 is a cross section taken on line 16—16 of Fig. 6 but showing certain added portions not shown in said Fig. 6 and also shows parts broken away;

Fig. 17 is a cross section taken substantially at elevation 17—17 of Fig. 4 but showing added elements of certain safety fill devices;

Fig. 18 is a cross section taken substantially at elevation 18—18 of Fig. 4;

Fig. 19 is a plan view of a valve plate and is taken substantially at elevation 19—19 of Fig. 4;

Fig. 20 is a sectional detail of certain telescoping filling tubes; and

Fig. 21 is a cam and valve diaphragm illustrating the coordinated operation of the device.

Corresponding reference characters indicate corresponding parts throughout the several views of the drawings.

General construction

Referring now more particularly to Figs. 1 and 2, there is illustrated at numeral 1 a base having an upper surface 3 machined on approximately a four degree slope, the purpose of which is to slope the apparatus as a whole, such that the supply tank 24 thereof will have a greater depth of liquid (ether) on one side than on another (see line A—A of Fig. 1). By sloping the machine in this manner, the effect to be described is attained, and yet all parts may be machined in the right angular relationships, such as are usually employed in machine construction.

The base 1 supports five members, namely, first, a punch press P of more or less conventional construction (the modifications required being noted herein), second, a standard S for supporting a cap supply tube 5,

third, a table T supported on suitable legs 7, fourth, an over traveling bracket B joined at its left end to said press P and at its right end to said base 1, and fifth, a base E for supporting the main frame and parts of the device.

The stationary base E supports a stationary spoked frame or wheel 9 carrying at its outer periphery a can-raising cam 11 and carrying on its inner hub a stationary cam 75 and valve plate 13 (see also Figs. 4 and 6 to 8).

An upstanding shaft 15 is rotatably borne by said base E and rests on an anti-friction ball 17 located within a suitable recess in 80 said base.

The shaft 15 is rotatable with respect to the wheel 9 and also to the valve plate 13 bolted to the wheel 9, the wheel 9 being prevented from turning with respect to the base 85 E by means of a crown or other suitable coupling 19.

At a short distance above the valve plate 13, the shaft 15 is provided with a flanged hub 21 made fast to said shaft. Outside of 90 the periphery of plate 13, the hub 21 engages with a can supporting wheel 23 (see Figs. 4, 6 to 8 and 14 to 18). The construction of wheel 23 will be described more in detail later.

The shaft 15 continues upwardly to a point 22 (Fig. 9) where it is shouldered and adapted to receive thereon (with a force fit and key connection) a supply tank 24 to the bottom of which is cast a flange 25 (see also Figs. 100 1 and 6 to 8).

Positioned between the flange 25 and the cam supporting wheel 23 is a peripheral cam track 27, supported by means of a bracket 29 extending to said table T, a bracket 31 extending to said bracket B and a bracket 33 extending to the cap supply tube 5. As will be seen later, the cam 27 is adapted to raise and lower certain annular nitrogen filling tubes 35 which telescopically cooperate with 110 certain stationary ether tubes 37 at points within the confines of said flange 25 (see also Fig. 20).

Dial feed mechanism M (see Figs. 1 to 3) 115

It is desired herein, to intermittently revolve the can-supporting wheel 23. The intermittent movement is to comprise thirty-two movements for each revolution in the present embodiment but it is to be understood that any other suitable number of movements may be employed.

In order to accomplish the result, thirty-two notches 39 are equally spaced in the periphery of said wheel. One of said notches 39 is adapted to be engaged by a spring pressed locking pawl 41 each time that the wheel 23 approaches a halt. The locking pawl 41 tends to maintain its position against 125

the wheel 23 because of a spring 53. The pawl 41 is pivoted on said table T. At the same time another one of said notches 39 is about to be engaged by another pawl 43 (pressed by a spring 45) said pawl 43 being pivoted to a slider 47 held in guides 49 located on said table T. The spring 45 is also mounted on said slider 47.

An arm 51 of the pawl 41 is normally held by the spring 53 so that the pawl engages the wheel 23. The spring 53 leads to a stationary pin 55. A plate 57, held fast to the slider 47, pivotally carries a releasing bar 59 adapted to engage a pin 56 on the plate 57 when the slider 47 moves to the right (Figs. 2 and 3). The other end of the bar 59 functions to wipe the arm 51 of the pawl 41 whenever the slider 47 starts its forward movement.

The slider 47 is moved back and forth by means of the oscillating movements of a bell crank 61 which is connected to said slide 47 by an adjustable connecting rod 63. The oscillations of the bell crank 61 are due to a connecting rod 65, moved by means of a crank pin 67 eccentrically located with respect to the crank shaft 69 of said press P. Adjustment of the throw of the slider 47 is obtained by moving the pin 67 in a slot 71 provided for in a crank disc 73 and the position of the throw (after its length is determined) may be adjusted at the rod 63.

The operation of the dial feed is as follows:

The shaft 69 rotates at a predetermined speed, being suitably geared to the drive shaft 75 of the press P, said drive shaft 75 receiving motion from a belt 77 and pulley 79. The motion comes from a suitable source, not shown. The linkage 65, 61, 63 and 47 is thereby oscillated. Movement starts from a position such as shown in Fig. 2. The pawl 43 moves a short distance without effect on the wheel 23. At this time the bar 59 opens the pawl 41 thereby releasing the wheel 23 for movement. Next, the pawl 43 drops into its respective notch and drives the wheel 23 forward one space. In the meantime the bar 59 passes over the arm 51 of the pawl 41, whereby the pawl 41 re-engages the wheel 23 to drop into the next notch 39 whereby the wheel is halted at a predetermined position.

Upon return of the slider 47, the pawl 43 automatically leaves its notch and the bar 59 is itself moved by a contact with the pawl 41 because of the resiliency of the spring 72. The pawl 41 is not withdrawn from its notch. Thus, for each revolution of the shaft 69 of the press the wheel 23 is positively advanced $\frac{1}{2}$ of a revolution.

Fig. 2 shows the dial feed mechanism M at the left-hand of its throw and Fig. 3 shows said mechanism at the right-hand end of its throw.

Can control

From the above it will be seen that the can wheel 23 moves intermittently and, in order to receive and later eject a can at each period of rest, the outer peripheral portion 81 of said wheel 23 is provided with thirty-two recesses or pockets 83, each one of which is adapted to snugly receive a can controller or pusher piece or movable pocket 85 (see Figs. 6 to 8 and 14 to 17). The pushers or pockets 85 are so formed that each one is adapted to snugly receive a can from a can supply mechanism K (Figs. 1, 2 and 21), that is, when the pusher 85 is in one of its retracted positions and the wheel 23 at a certain point of rest.

Each pusher 85 is provided with a slidable slotted arm 87 arranged radially of the wheel 23 in polygonal or rectangular guides 89. Each slotted arm 87 has fastened at its inner portion a radially arranged stem 91 borne in a bearing 93, also formed in said wheel 23. The inner ends of the stems 91 are provided with upwardly extending roll followers 95 which engage a cam track 97 formed in the lower surface of said stationary valve and cam plate 13. The track 97 has the form shown in Figs. 14, 15, 19 and 21.

It will be understood from the above, that the cam and valve plate 13 is stationary and that the shaft 15 rotates the wheel 23 (by means of the hub 21) with the radially sliding pusher members described. The engagement of the moving roll followers 95 with the stationary cam track 97 results in said pushers 85 receiving a radially outward and inward movement once for every revolution of the wheel 23. They cannot twist out of alignment because of the polygonal bearings or guides 89.

As will be seen hereinafter, the press P is stationed at the radial apex of the track 97 and hence the pushers 85 are adapted to push cans outwardly from the wheel 23 when the press station PS is reached (see Figs. 1, 8, 14, 15 and 21). The cam track 97 is so shaped that by the time the can supply station CS is reached, the pushers 85 have been again retracted. They then remain retracted until need for their outward movement is again required near and at the press station PS.

Can supply means K

The conventional can supply means K is illustrated in Figs. 1 and 2 and comprises two angle irons 99 arranged in parallel spaced relationship and leading to a point flush with the outer platform-like surface of the wheel 23. A belt 101 operates between the irons 99 and functions to continually press cans D along the guide 99 into the wheel 23. It is continually slipping on the bottoms of the cans D and is fed over a pulley 103. A

portion of the can supply means K is broken away at Q in Fig. 1 for purposes of clarity but Fig. 2 shows the continuity of the construction.

- 5 The can supply station CS for this can supply means is so arranged that when the wheel 23 stops, a can D is pushed into the pocket or pusher 85, which pusher is then in retracted position ready to receive the can D.
- 10 As the wheel 23 makes its next movement the said can D is carried away with the wheel 23, being prevented from falling out of the wheel 23 by a rail 105 formed therearound and held on suitable supports 34. As each
- 15 can D moves away in the wheel 23, the next one is automatically pushed into the next pusher 85. The wheel 23 is thus being continuously loaded at the can supply station CS.

20

Filling control means

As each can D is pressed into its pocket or pusher 85, it engages a control pin 107 (see Figs. 6 to 8 and 17). Each pin 107 is 25 slidably borne in the wheel 23 and extends loosely through its respective pusher 85, thereby providing means for permitting movement of the pusher independently of the pin. An inner head 109 of each pin 107 bears 30 against an actuating arm 111, said arm 111 being fastened to a hollow rotatable rod 113 rotatably borne at points 115 within the wheel 23. This rod 113 has fastened at its lower end a lug 117 pivotally carrying an 35 actuating piece 119. The hollow rod 113 is normally pressed counter-clockwise (viewed from above) by a spring 121 so that said actuating piece 119 is not adapted to engage a peripherally arranged lifting cam 123 on 40 the wheel 9 but lies directly on said wheel (see Fig. 8). The outer end 125 of each actuating piece 119 is adapted to engage a lifting stem 127 of the valve system of the next adjacent valve system, that is, when 45 the actuating piece is rotated clockwise into such a position that it is adapted to engage the cam 123 as the wheel 23 moves. Each lifting stem 127 is slidably arranged in one 50 of the hollow rods 113. Clockwise positioning of each actuating piece 119 is accomplished when a can enters the pusher 85. This positioning is accomplished against the tension of the spring 121, so that if no can 55 is so positioned, the piece 119 will not ride on the cam 123 to actuate the next successive stem 127, which is the stem for the can in question. Each can functions its own stem 127 but each stem 127 is slidably borne in the bearing piece 113 adapted to actuate the 60 next successive stem 127 (see Fig. 17). However, whenever a can is so positioned, the actuating piece 119 is thrown so that it may ride on the cam 123 and thereby be caused by the cam 123 to actuate the next successive 65 stem 127.

By referring to Fig. 9, it will be seen that the actuating rods 127 pass upwardly into bearing and sealing tubes or glands 129 located in the supply chamber 24. There each one is equipped with an overhanging arm 131 which controls the movement of a spring pressed ether valve 133 adapted to permit emptying of a measuring cup 135 into one of said vertically stationary ether supply pipes 37. Each of the supply pipes, as will be 75 seen later, is adapted to supply ether to a can D.

From the above it is evident that if, due to one cause or another, one of the pushers 85 should fail to receive a can there is no possibility of ether flowing and spilling out of its respective fill tube, because no can is present to actuate the member 119 so that said member 119 is controlled by the cam 123. In other words, in order that the cam 123 may become effective to cause opening of an ether valve 133, it is necessary that a can be positioned in the respective pocket. If a can is not so positioned the actuating member 119 will not engage the cam 123. It is now evident that the rail 105 also maintains the cans in their respective places against the pressure of the pins 107. It is also evident that the slots 137 in the arms 87 are for the purpose of clearing the stems 127.

Can lifting means

In order to lift each can (for purposes to be described) as it moves around with the wheel 23, there is provided beneath each movable pocket of the pusher 85 and elevator 139 slidably arranged in the wheel 23 (Figs. 6 to 8). The top of the elevator 139 is flush with the surface or platform of the wheel 23, that is, when said elevator is in its lowermost 100 position. In order that the elevator 139 may be raised and lowered, the cam 11 is arranged on the rim of the stationary wheel 9 to engage the lower ends of said elevators 139. A lowered position of the elevator 139 is shown in Fig. 6 and an elevated position in Fig. 7.

Can filling heads

The purpose of lifting the cans D is to seal their nozzles 143 against contact with the atmosphere during the packaging operation. For this purpose, a ring 145 is bolted to the wheel 23 for the purpose of mounting thereon thirty-two sealing heads 147 (Figs. 6 to 8 and 16). The heads are so arranged that they form a practically continuous peripheral surface 149 for purposes to be made clear (see Fig. 16). The ring 145 provides the polygonal bearings or guides 89, referred to above.

Each head 147 (see Figs. 6 to 8 and 16) comprises a casting 151 bolted to said ring 145. The ring 145 is provided with slightly tapering holes 153 adapted to receive in sealing contact lower portions 155 of said castings 151. The lower portion 155 of each cast-

ing 151 carries a rubber bead or gasket 157 for engagement with the top of the can D when said can is lifted in the manner hereinbefore described. The nozzle 143 is at this 5 stage positioned in a recess 159 (see Fig. 7).

Each casting 151 carries a length 161 of a cap supply line or tube. The cross section of the length 161 is of such a form that a 10 passage 163 is left beneath caps F carried in said length 161. Two caps are normally carried in the length of tube 161 and the opening of said length 161 is provided with a gate valve 165 adapted to cut off communication with the atmosphere when the valve is down 15 and to permit a cap supply when the valve is up.

The valve 165 is raised by cooperation of an ear 167 thereon with a cam 169 positioned on 20 said cap supply tube 5 (see Figs. 2, 6 and 16).

The can caps F are fed down tube 5 by gravity and the foremost one normally rests against 25 said peripheral surface 149. As successive passages 161 align with the supply tube 5, the gate valves 165 thereof automatically open, whereby the weight of the caps F in the tube 5 is adapted to push the foremost cap against the two caps in the passage 161. By this means of foremost cap in the passage 161 is positively pushed into position between the 30 tines of a horseshoe shaped leaf spring 171. As the wheel 23 moves on, the gate valve 165 drops shut.

Prior to the above described cap placing 35 event, certain other filling events are adapted by to take place. These are accomplished by arranging said annular nitrogen tube 35 in a slidable fashion in a stuffing gland 173 of said head 147 (see Figs. 6 to 8 and 20). This tube extends upwardly through a gland 175 40 and into said flange 25 where it telescopes the said stationary ether tube 37, the inner portion of the annular nitrogen tube forming a downward continuation of the ether tube. The tube 35 has a sideward opening 177 at 45 its upper end and has a mouth 179 at its lower end.

In all positions of the tube 35, the opening 177 communicates with a slot 181 within the flange 25, said slot in turn communicating 50 by way of a tube passage 185 with a valve port 183. At a suitable distance above its mouth 179 the tube 35 is provided with a plurality of openings 187 for ejecting nitrogen only. The tube 35 is shown in retracted 55 position in Fig. 6 and in a downward position in Fig. 7. Its movement is controlled by means of said cam 27 actuating a follower 189, said follower being joined to the tube 35 by means of a resilient spring connection 191.

60 A guide 193 maintains each follower 189 in proper alignment.

The said port 183 forms part of short circuiting valve 195 formed integrally with the casting 151. The valve 195 is provided 65 with an inlet port 197 reaching from a point

of communication 199 with said cap passage 161. Said valve 195 has an outlet port 201 and an inlet port 203 provided with suitable piping 211, 213, to be described.

The valve 195 is bored to receive a hollow 70 stem 205 provided with suitable plugs 207 adapted to bring about the connections to be set forth. A spring 206 normally holds down the stem 205. The stem 205 is slidable in the valve 195 and is provided at its lower end 75 with a feeler 209 adapted to be engaged by the can D when the can is lifted.

The operation will be best understood by setting forth the function in view to Figs. 6 to 8. In Fig. 6 the can D has just been 80 placed in the recess of the pusher 85. The actuating member 119 has been turned so that when the cam 123 is reached the stem 127 will be actuated. The tube 35 is up and can D is down. The feeler 209 is down. Nitrogen flowing in over the line 211 is short circuited out of the valve 195 into the line 213 to pass to a point later to be described. No nitrogen is flowing through the passage 185. The tube 35 is retracted and the ether valve is closed. 90

In Fig. 7 the can D is shown in raised position and forming a seal with the gasket 157, a high portion of the cam 11 having been reached. The caps F are in their original 95 positions and the spring 171 is empty. The cam 27 has forced the annular tube 35 down into the raised can D to a point near the bottom. The feeler 209 has been raised whereby the valve 195 is put into the Fig. 7 position. The actuating piece 119 has ridden up on the cam 123, whereby the ether valve has been 100 caused to be opened. The net result is that ether is flowing into the can D and at the same time nitrogen from the line 211 is passed through the valve 195, through the passage 185, slot 181, opening 177 and down the tube 35. The nitrogen flows out of the mouth 179 and forms a jacket around the flowing ether coming out of the central mouth 215, thereby tending to complete the protection 105 of the ether by the nitrogen. As the can D fills, the nitrogen flows out of the nozzle 143, up around the air laden caps F and to the inlet port 197 by way of the communication 110 199. From here it passes to said pipe 213 to certain valved recesses in the central valve and cam plate 13 (to be described, see Fig. 4) and thence back over the next line 211 in order.

From the above, it will be seen that as the 120 ether level in the can D rises, that the outlet mouths 179 and 215 of the tube 35 are cut off. This does not effect the flow of ether, because of the liquid head thereabove, but it cuts off the flow of nitrogen which, from 125 that time on, flows from the said row of holes 187. As will be seen later, the nitrogen gas is saturated with ether for the purpose of weighting it so that it forms a blanket between the ether in the can, on which it

settles, and the air which it is displacing upwardly. The purpose of forcing the nitrogen out past the caps in the length 161 is to force out and absorb air from these caps so that they will not later contaminate the ether in the cans. It is evident that the function of the nitrogen gas is both to displace air and to diffuse with it.

- 10 The relative timing of the machine components will be given later, after the component operations thereof have been made clear. It suffices at this time to say that the next general movement is the upward retraction of the tube 35 as the ether valve is closed. The nitrogen gas is then cut off by the means to be described. Then, before the can descends, the tail portion 167 of the gate 165 reaches the cam 169 to be opened thereby as the wheel 23 comes to a halt, 15 whereupon the foremost cap of the pair in the casting 151 is pushed out into the spring 171 directly over the nozzle 143 of the can D. The next movement comprises the descent of the can (because of a depression in the cam 11), including a short depression and 20 retraction of the tube 35, (because of a depression 215 in the cam 27, see Fig. 1). The follower 189 is caused to go downwardly at a slightly faster rate than the can D and the 25 differential movement taken up by the resilient spring connection 191 between said follower and the tube 35. By this means the end of the tube 35 (no ether or nitrogen is 30 flowing at this time, as will be seen later) 35 is caused to punch the cap out of the spring 171 and align it on the nozzle 143. This action also positively starts the can down and, if desired, may be timed to seat the can in its lower position. 40 After this, the tube 35 is again retracted and the can is later pushed into its Fig. 8 position and out beneath the die head of the press (see Fig. 13).

45 *Counter flow and counter diffusion mechanism.*

- 50 In order to produce a counter diffusion and counter flow or current of nitrogen through the advancing air-filled cans, the mechanism shown in Figs. 4, 16, 18 and 19 is used. This mechanism comprises said stationary valve and cam plate 13, in the upper surface of which are cut a series of connected recesses 55 shown in Fig. 19. These recesses comprise in part an outer row of recesses 217 and an inner row of recesses 219. For thirteen of the thirty-two divisions of the circle there is one recess 217 and one recess 219 forming 60 pairs. Each recess 219 communicates with the recess 217 of a subsequent pair of recesses. This, as stated, continues for thirteen divisions of the circle.

65 The next nine divisions of the circle are divided into three parts by inner and outer

recesses 221 and 223 respectively, similar to said recesses 219, 217 but each one taking up three times as much circular arc as the short recesses.

70 A nitrogen supply line 225 communicates with the last of the inner recesses 219 and 221 and a nitrogen outlet line 227 communicates with the first of the outer recesses 217 and 223. All recesses are separated from one another a suitable distance for cutting off a 75 fluid supply as ports pass over the recesses. The direction of port movement is shown by arrow S (Figs. 19 and 21).

80 The top face of the plate 13 is machined and receives thereon a machined plate 229 having suitable oiling grooves 230 and an oiling system therefor, whereby a gas-tight cover is formed for the plate 13. The plate 229 is driven from the wheel 23 by loose 85 splines 231 and is spring pressed by means of six springs 233 adjustably backed by hollow nuts 235. The spring pressure on the plate 229 compensates for possible misalignment between the hub 21 and the stationary 90 plate 13.

95 The plate 229 is provided with thirty-two pairs of equally spaced outer and inner nitrogen pipes 237, 239. These pipes pass loosely through the hub 21 and communicate with the outer and inner rows of recesses in the plate 13. The outer row of pipes 237 are joined by flexible connectors 241 to said pipes 213. The inner row of pipes 239 are 100 flexibly joined by flexible connectors 243 to 105 said pipes 211. The arrows in the drawings show the flow lines. A bracket 242 located between the hub 21 and wheel 23 supports the pipes 211, 213. The coupling between the hub and wheel permits access to the plate 105 229.

110 As consecutive pairs of communicating pipes 237, 239 bridge the pairs of recesses 217, 219 in the plate 13, said pairs of recesses are caused to communicate in the following 110 manner:

115 If the can is not raised or no can is in position (see Figs. 4 to 6, 8 and 19), the nitrogen passes from an inner recess 219 of the plate 13, through the pipe 239, connector 243, pipe 211, valve 195 (set to short circuit because no can D is lifting the feeler 209), pipe 213, connector 241, pipe 237, and outer recess 217. If the outer recess 217 happens to be the first 120 one engaged (movement of the wheel 23 is counter-clockwise), then the gas exhausts out over the line 227 (see Fig. 5). If said recess 217 is not the first one but a subsequent one, the charge of nitrogen gas (which has previously been diffused with air in a prior can) passes to the next inner recess 219 by way of one of the cross connections 240 shown in Fig. 19. It then passes through the next can 125 in its diluted form.

If a can is in raised position, as shown in Fig. 7, the nitrogen passes from an inner recess 219 of the plate 13, through the pipe 239, connector 243, pipe 211, valve 195, set to feed nitrogen up into the pipe 185, port 177, pipe 35, can D, communication 199, valve 195, pipe 213, connector 241, pipe 237 and outer recess 217.

Thus it will be seen that nitrogen passes back and forth from recesses 217 to recesses 219, by way of the cans themselves unless the cans are short circuited and in the latter case the counter flow of nitrogen is not stopped but may pass on to other cans which are in position. The effect of the above method of displacing and diffusing air by a counterflow is that it is done with a high economy of nitrogen. As the cans proceed counter-clockwise around the circle for thirteen divisions the nitrogen percentage increases in the nitrogen-air mixture, because the source of supply 225 of nitrogen is being approached.

As will be seen later, the ether valve is opened at the twelfth division and soon fills the can so that the lower nitrogen outlet of the tube 35 is quickly closed. After that, the nitrogen flow is slower through the openings 187. Hence, three of the previously smaller recesses 219 of the plate 13 are formed as one recess 221 and three of the recesses 217 are formed as one recess 223. The cross connections 240 are retained. It is evident that by this means, sets of three cans exhaust in parallel to the next succeeding set of three cans, instead of can by can as above described. Hence the flow of gas is not throttled, even though the cans are almost filled. They are filled to a point just below the openings 187, considering the tube 35 as being down. Fresh nitrogen is fed into the last inner recess 221 by means of the line 225. It displaces and diffuses with the air and nitrogen (mostly nitrogen when the cans arrive at the last division). Each can as it moves into a new position, receives a stronger nitrogen-containing gas, whereby more and more air is displaced and diffused until, when the can reaches the last position, practically no air is left and the fresh nitrogen completely protects the ether.

It will be seen from the above that the term counter diffusion, as used herein, refers to the fact that in a series of containers, movement is so effected and connections are so made that the undesirable contents of a container are diffused with slightly more desirable material from the next preceding container, the then diffused products in the container in question being ejected to the next succeeding container which has slightly less desirable material therein. The term also includes the last diffusion of the almost correct material had in the containers by the pure incoming desirable protective gas.

Ether and nitrogen supply (see Figs. 1, 2, 4, 5 and 9 to 12)

The ether supply tank 24 is supported by and moves with said shaft 15. It is preferably constructed of aluminum throughout and has a shell 243 surrounding the shaft 15. It is also provided with an air-tight cover 245. The shell 243 reaches upwardly a distance great enough to form a bearing 247 for a sliding sleeve 249, said sleeve 249 being screwed to a spider 251 having thirty-two arms 253 reaching out to points in proximity to said ether measuring cups 135 within the tank. Displacement fingers 255 reach from the arms 253 into the respective cups 135. The upper reduced end 257 of the shaft 15 is threaded for the reception of a hand wheel 259 (Fig. 10) adapted to control the vertical movement of said sleeve 249, without necessarily rotating said sleeve. The sleeve, with the spider 251 is prevented from rotating because of the upstanding bearings 129 for the valve lifters 127. By means of this mechanism the thermal expansion and contraction of the ether in all of the measuring cups 135 may be compensated for at one movement.

The bracket B, which extends over the machine as a whole, supports a stationary circular sleeve casting 261 (Fig. 10) which aids in slidably supporting said sleeve 249 and also provides means for mounting a stuffing gland 263 in connection with the lid 245. The lid 245 of the supply chamber 224 of course rotates and it is highly desirable to exclude air from the ether supply and to conserve nitrogen. A plus pressure thereof is carried in the tank 24.

As illustrated in Figs. 10 to 12, the casting 261 is provided with several openings. One of these slidably receives a valve stem 264 vertically operable by means of a float and lever 265 pivoted to a trough 267 located at the lower end of the casting 261.

The purpose of the trough 267 is to catch any oil which may descend from the gland 263 and the purpose of the stem 264 is to operate a conventional air valve 269 as the level of the ether in the tank 24 descends.

When the air valve 269 opens, (receiving 115 its supply from a conventional source 271) air is permitted to flow to a conventional diaphragm valve 273 (see Fig. 12). This causes the valve 273 to open and because it is a valve in the ether supply line 275 said ether 120 coming from a suitable source (not shown), thereby is permitted to flow. It flows into a port 277 passing through said casting 261 and a head 262 thereon. This ether flows straight down to a point below the trough 125 267 and into the ether supply whereby the level is again raised, and the valves 269 and 273 shut off. By this means a constant level 130 of ether is maintained in the tank 24. Nitrogen is brought from a gasometer (not shown)

by way of the line 276 connecting with a passage 279 in said casting 261 and head 262 (see Fig. 10). The passage 279 is adjacent the ether passage 277, whereby the ether and nitrogen are well mixed by the splashing effect as the ether falls. The nitrogen is thus weighted with miscible ether particles.

A slight plus pressure is carried in the line 276 and consequently in the tank 24.

10 Nitrogen is led from the tank by way of a pipe 278, communicating with a separated passage 281 in said casting 261. The passage 281 does not go to the bottom of the casting 261 (Figs. 10 and 11).

15 Said pipe 278 reaches to a point adjacent the edge of the supply tank 24. Hence nitrogen will not short circuit through the tank 24 but will fill and circulate through it. The nitrogen outlet passages 281 communi-
20 cates with said nitrogen line 225, referred to hereinbefore as the inlet line for the stationary valve plate 13 (see Figs. 4 and 19). The slight plus pressure of nitrogen carried in the tank 24 results in there being no possi-
25 bility of leaking air into said tank to spoil the ether. This pressure also maintains the circulation of the nitrogen throughout its subsequent circulation.

30

The press P

The press P is per se of conventional construction. It comprises the ordinary frame 285 having an overhanging head 287 which supports the slider crank mechanism 289 for reciprocating the head 291 thereof. Said drive shaft 75 operated by the belt and pulley 77, 79 is geared to the crank shaft 69. The crank shaft controls the reciprocations of the head 291 in the usual manner.

40 The head 291 (Fig. 13) carries two spurs 293 slidably passing through a slot 295 in a bolster plate 297, said bolster plate 297 being fastened to the press frame 285. The head 291 is shown in its uppermost position

45 in Fig. 13. Screwed to the bottom of the bolster plate 297 (see also Fig. 14) are two guides 299 for slidably supporting a pair of underslung clamping die blocks 301. Slots 303 in the blocks 301 are engaged by said spurs 293, the purpose being that when the spurs descend the die blocks will be clamped together to pinch the lower portions of the cap around the nozzle, and at the same period a die 305 fastened to the head 291 presses

50 the cap home. Further details of this die closing construction will not be gone into at this point because it is disclosed in detail in Patent No. 1,418,114 dated May 30, 1922. After the described die press opera-
55 tion is completed the head 291 retracts and the blocks 301 automatically open under pressure of opening springs 307 (see Fig. 14).

Reference to Figs. 1, 13 and 14 show that there is integrally formed with the bolster plate 297 a take-off plate 309 cooperating

with the flat peripheral surface of the wheel 23. Furthermore, the said rail 105 passes out around the edge of said plate 309. Fig. 15 shows how the cam track 97 functions to move the pushers 85 radially after the cans have descended after having been filled and a cap aligned thereon. The pushers gradually force the cans out, because of the intermittent movement, until one each is successively placed below and between the die 305 and blocks 301. A resiliently mounted plate 304 provides means for supporting the cans against blows from the die 305. During a rest period the cap is tightly closed by the press, after which the press reopens and during the next intermittent movement the can is moved on by the pusher 85. As it moves on it rides out over a strip of saw steel 311 fastened to the edge of the plate 309 which is adapted to carry the can out onto a moving belt 313 which takes the cans away, ready for sale. The next intermittent movements of the wheel 23 cause a retraction of the pushers 85 until the can-filling station CS is reached, when the pushers are completely retracted.

Timing diagram (Fig. 21)

CS represents the line of cans D coming in over the can supply mechanism. As the cans enter the wheel 23 they are swept side-
wardly into a circular movement, being held in position in the pushers 85 and by the rail 105.

During the first intermittent movement of a can in the wheel 23 the slope of the cam 11 is such as to lift the can into cooperation with the head 147 (see also Fig. 7). At the same time the fill tube 35 is brought down by proper curvature of the cam 27 (see also Fig. 7). This positioning of the can and fill tube occupies one movement. For the next series of movements the can and fill tube remain in this position.

At the second movement of the can D the pipes 237, 239 communicate with the gas transmitting recesses 219, 217. Hence the cans are gassed in series by nitrogen in the manner described, comprising a counterflow of nitrogen and air, during the process of which diffusion proceeds, as well as displacement. This state of affairs is continued for twelve movements, that is through the thirteenth movement, that is, taking the can supply station CS as a reference.

The cam 123 becomes effective to open the ether valve during the fourteenth movement. This fourteenth movement is the last one during which the pairs of unitary recesses 219, 217 are effective. Soon after the ether valve opens the can fills up to a level above the outlet 179 of the pipe 35 and thereafter during the fifteenth through the twenty-third movements the pairs of triplicate recesses 223, 221 are used, that is, in order to

prevent throttling through the relatively restricted openings 187.

Ether and nitrogen flow into the can during the fourteenth through the twenty-second movement. Nitrogen continues to flow for about one-half of the twenty-third movement. At about one-half of the twenty-first movement the cam 27 is so formed as to begin to withdraw the fill tube 35. The fill tube 10 is completely drawn up as the last of the gas-sing recesses 223, 221 are passed over.

The cam 169 on the cap supply tube 5 is effective to open the gate 165 said opening being a maximum at the end of the twenty-15 third movement. This action supplies a cap to the spring 171. The can is still up at this time. The cap supply station is marked FS in Fig. 21.

At the twenty-fourth movement cam 169 20 permits the gate 165 to close and at the same time the cam 11 causes the can D to descend. At this same period the cam 27 causes the fill tube to be momentarily depressed in order to push the cap out of the spring 171 25 down on the nozzle 143. The spring engagement 191 (Fig. 7) makes this possible and also tends to positively push down the can.

The elevation of the can at the end of the twenty-fourth movement is the same as it was 30 at the beginning of the first movement but the can is now filled, having first been gassed to remove the air and it also has a cap resting thereon.

The twenty-fifth through the twenty-35 eighth movements are consumed in pushing the can out onto the platform 309 and between die blocks 301 of the press P. At the end of the twenty-eighth movement the press is timed to hermetically apply the cap to the 40 can. Before the beginning of the twenty-ninth movement the press has again permitted opening of the die blocks 301. The press station is indicated by indicia PS in Fig. 21.

The twenty-ninth movement is consumed 45 in pushing the can from its position between the blocks 301 to a position on the belt 313 by means of which it is carried away. The take-off belt station is indicated by the indicia BS in Fig. 21.

The thirtieth through the thirty-third movements are consumed in retracting the pusher 85 so that it is in position to again receive a can at the can-filling station CS.

55 Outward radial directions on the diagram represent upward cam action and inward directions represent downward cam action.

Measuring means

60 The thermal compensating means for the ether cups 135 (see Fig. 9) has been described in connection with the tank 24.

The machine as a whole is slanted as shown in Fig. 1, whereby the cups 135 are caused to 65 dip under the ether level on the deep side and

to emerge therefrom on the shallow side. They are thus filled. The high level line is shown by letters HL in Fig. 9 and the low level line by letters LL. Fig. 1 illustrates that the general direction of the slope is toward the press P but it is to be understood that the exact slope is such that the mouths 136 of the cups 135 are above the liquid level when the ether valves 133 open. Each time that a cup passes through the low region of the machine (through the deep portion of the ether pool in the tank 24) it picks up an accurate charge (adjustable from the wheel 259). This charge of ether is not emptied until the mouth 136 of the cup moves out at the shallow side of the pool and the ether valve is opened.

It is to be understood that the ether for filling the cans is received in a pure condition from a suitable manufacturing process and this is also true of the nitrogen. The used nitrogen is taken from the present machine (see line 227) and sent to a reclaiming device for extracting and reclaiming the ether used in the described weighting process.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

1. The method of packaging a substance comprising removing a deleterious fluid from a plurality of packages by causing a counter diffusion between said deleterious fluid and a non-deleterious fluid, said non-deleterious fluid having been weighted with a quantity of the said substance being packaged so as to be heavier than said deleterious fluid.

2. The method of packaging a substance comprising removing a deleterious fluid from a plurality of packages by causing a counterflow between said deleterious fluid and a non-deleterious fluid, said non-deleterious fluid having been weighted with a quantity of the said substance being packaged so as to be heavier than said deleterious fluid, said substance being packaged being heavier than either of said fluids.

3. The packaging method comprising simultaneously displacing and counterdiffusing deleterious fluid in a series of packages by and with a non-deleterious fluid and filling the fluid to be packaged in behind the non-deleterious fluid in the last of said series of packages, said non-deleterious fluid being weighted with portions of the fluid being packaged.

5 of said exhaust ports in communication with a plurality of non-deleterious fluid supply pipes, whereby series connections are made through a plurality of said packages, means for short-circuiting the connections through any given head, means for supplying caps to said packages through said heads, said last-named means preventing passage of air to the packages and means for preventing ether flow when a package is not in receiving position.

10 11. Means for introducing ether and a non-deleterious fluid into a series of packages comprising a plurality of heads, means for moving the packages into sealed communication with said heads, ether and non-deleterious fluid supply pipes movable through said heads, means for introducing said pipes into the packages whereby said packages may be gassed by said non-deleterious fluid and supplied with ether and an exhaust port in each head for receiving displaced fluids, and means for causing said exhaust port of each head to exhaust to the next successive package.

15 12. Means for introducing ether and a non-deleterious fluid into a series of packages comprising a plurality of heads, means for moving the packages into sealed communication with said heads, ether and non-deleterious fluid supply pipes movable through said heads, means for introducing said pipes into the packages whereby said packages may be gassed by said non-deleterious fluid and supplied with ether and an exhaust port in each head for receiving displaced fluids, and means for causing said exhaust port of each head to exhaust to the next successive package and means providing a direct diversion 20 of non-deleterious fluid to the next successive package whenever a given preceding package is missing.

25 13. The method of packaging a substance comprising weighting a non-deleterious fluid with a material heavier than a deleterious fluid and removing the deleterious fluid from a plurality of packages by causing a counter-diffusion between said deleterious fluid and the weighted, non-deleterious fluid.

30 14. The method of packaging ether comprising weighting nitrogen with ether vapor, and removing the deleterious fluid from the package by causing a counter-diffusion between the deleterious fluid and said weighted nitrogen fluid.

35 15. The method of packaging ether comprising weighting nitrogen with ether vapor, removing a deleterious fluid from a plurality of packages by filling said packages with said weighted nitrogen, and partially filling said packages with ether and sealing the same.

40 16. The method of packaging ether comprising weighting nitrogen with ether vapor, and removing a deleterious fluid from a plu-

rality of packages by filling said packages with said weighted nitrogen.

45 17. Apparatus for packaging ether comprising means for moving a package having air therein, means for producing a counter movement of nitrogen through the package and the air therein, means for impregnating the nitrogen with ether comprising a body having therein a chamber adapted to contain ether and means for passing the nitrogen through said chamber, and means for filling said package with ether.

50 18. Apparatus for packaging ether comprising means for moving a package having air therein, means for producing a counter movement of nitrogen through the package and the air therein, means for weighting said nitrogen and means for filling said package with ether.

55 19. Apparatus for packaging ether comprising means for moving a package having air therein, means for producing a counter movement of nitrogen through the package and the air therein, means for impregnating the nitrogen with ether comprising a body having therein a chamber adapted to contain ether and means for passing the nitrogen through said chamber, and means for filling a measured charge into said package.

60 20. Apparatus for packaging ether comprising a body having therein a chamber adapted to contain ether, means for moving a package having air therein, means for producing a counter movement of nitrogen through the package and the air therein, means for passing said nitrogen through said chamber containing ether, prior to said counter movement, whereby said nitrogen is impregnated with ether, and means for filling a measured charge into said package comprising a measuring cup in communication with the package and adapted to pass above and below the surface of the ether in said chamber.

65 21. Apparatus for packaging ether comprising a body having therein a chamber adapted to contain ether, means for moving a package having air therein, means for producing a counter movement of nitrogen through the package and the air therein, means for passing said nitrogen through said chamber containing ether, prior to said counter movement whereby said nitrogen is impregnated with ether, and means for filling a measured charge into said package comprising a measuring cup in communication with the package and adapted to pass above and below the surface of the ether in said chamber, and means for compensating the charge in said cup as the temperature changes.

70 22. Apparatus for packaging ether comprising a body having therein a chamber adapted to contain ether, means for moving a package having air therein, means for producing a counter movement of nitrogen

through the package and the air therein, means for passing said nitrogen through said chamber containing ether, prior to said counter movement, whereby said nitrogen is impregnated with ether, and means for filling a measured charge into said package comprising a measuring cup in communication with the package and adapted to pass above and below the surface of the ether in said chamber, and means for maintaining a predetermined level of ether in said chamber.

10 In testimony whereof, we have signed our names to this specification this 1st day of

15 March, 1927.

EDWARD MALLINCKRODT, JR.
HENRY V. FARR.
